 PLLC; Timothy DeWitt(57) **CLAIM**

The ornamental design for an electrosurgical generator, as shown and described.

DESCRIPTION

FIG. 1 is a perspective view of the electrosurgical generator; FIG. 2 is a front view of the electrosurgical generator; FIG. 3 is a back view of the electrosurgical generator; FIG. 4 is a left side view of the electrosurgical generator; FIG. 5 is a right side view of the electrosurgical generator; FIG. 6 is a top view of the electrosurgical generator; and, FIG. 7 is a bottom view of the electrosurgical generator. In FIGS. 1, 2, 3 and 6 the text shown is for the purpose of showing surface ornamentation only and forms no part of the claimed design. In FIGS. 3 and 7 the broken lines are for the purpose of illustrating portions of the electrosurgical generator that form no part of the claimed design.
